UNITED STATES PATENT OFFICE.

GUSTAVE D. GLASER, OF CHICAGO, ILLINOIS, ASSIGNOR TO GLASER, KOHN & CO., OF SAME PLACE.

DESIGN FOR A BOTTLE.

SPECIFICATION forming part of Design No. 19,864, dated June 3, 1890.

Application filed April 25, 1890. Serial No. 349,888. Term of patent 7 years.

To all whom it may concern:

Be it known that I, GUSTAVE D. GLASER, a citizen of the United States, residing at Chicago, in the county of Cook and State of Illinois, have invented and produced a new and original Design for Bottles; and I do hereby declare the following to be a full, clear, and exact description of the same, reference being had to the accompanying drawings, forming a part thereof.

Figure 1 is a side view of the bottle, showing the raised panel. Fig. 2 is a sectional view of the bottle, taken on the line $x-x$ of Fig. 1.

15 The design consists in the shape or configuration of the bottle, the main body of which is in octagonal form, curving upward and inward from a point about centrally of its height to the mouth portion, with the mouth 20 portion made in cylindrical form, with a bead formed at the point of junction between the curved sides of the octagonal portion and the cylindrical mouth, and having a raised panel in oblong rectangular form and extending 25 diagonally across the face of the main body.

Referring to the accompanying illustration by letter, A indicates the bottle, which, from its outline in elevation, is of tapering form, and composed of a number of sides, which 30 give it an octagonal cross-section, the sides a

extending from the bottom in an upward and perpendicular direction to about one-half its height, from which point the sides and angles curve upward and inward to the mouth portion b. The mouth portion b is cylindrical 35 and provided with a small bead at its lower extremity, and as the sides approach this mouth portion b they taper to conform to the decrease in circumference of the bottle and at the same time to preserve the general form 40 and longitudinal curves of the bottle. The portion B is raised to set up a panel. This panel is formed on the bottle in an oblique position, while its surface is curved and presenting in appearance a label carelessly applied to the bottle. To complete this effect the edges of the panel B have a series of beveled scalloped portions c, the scallops connecting at the angles of the sides a.

Having now described my design, what I 45 claim is—

The design for bottles, substantially as herein described and shown.

In testimony whereof I affix my signature in presence of two witnesses.

GUSTAVE D. GLASER.
